(57) **CLAIM**

The ornamental design for a phototherapy mask as shown and described.

DESCRIPTION

The patent or application file contains at least one drawing executed in color. Copies of this patent with color drawing(s) will be provided by the Office upon request and payment of the necessary fee.

FIG. 1 is a perspective view of a phototherapy mask showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof;

FIG. 7 is a bottom elevational view thereof;

FIG. 8 is another perspective view thereof; and,

FIG. 9 is a reference view presenting the situation that LEDs are turned on to emit light under use.

The color portions of the phototherapy mask form no part of the claimed design.
